US0D1112995S

(12) United States Design Patent (10) Patent No.: US D1,112,995 S
(45) Date of Patent: * Feb. 10, 2026

(54) PET STAIRS

(71) Applicant: Shenzhen Simao Trade Co., Ltd.,
Shenzhen (CN)

(72) Inventor: Huishan Liu, Quanzhou (CN)

(73) Assignee: Shenzhen Simao Trade Co., Ltd.,
Shenzhen (CN)

() Term: 15 Years

(21) Appl. No.: 29/939,955

(22) Filed: Apr. 30, 2024

(51) LOC (15) Cl. 30-03

(52) U.S. Cl.

USPC D30/199
